The ornamental design for a plastic bag with color strip, as shown and described.

DESCRIPTION

FIG. 1 is a perspective of a plastic bag of the present invention having a color strip on a front flap of the plastic bag;

FIG. 2 is a front elevation of the plastic bag of FIG. 1;

FIG. 3 is a rear elevation;

FIG. 4 is a bottom plan;

FIG. 5 is a magnified detailed view of part of FIG. 4;

FIG. 6 is a top plan;

FIG. 7 is a right side elevation;

FIG. 8 is a left side elevation;

FIG. 9 is a front elevation of a second embodiment of the invention, the front flap of the plastic bag being lined for the color violet;

FIG. 10 is a front elevation of a third embodiment of the invention, the front flap of the plastic bag being lined for the color blue;

FIG. 11 is a front elevation of a fourth embodiment of the invention, the front flap of the plastic bag being lined for the color green;

FIG. 12 is a front elevation of a fifth embodiment of the invention, the front flap of the plastic bag being lined for the color yellow;

FIG. 13 is a front elevation of a sixth embodiment of the invention, the front flap of the plastic bag being lined for the color orange;

FIG. 14 is a front elevation of a seventh embodiment of the invention, the front flap of the plastic bag being lined for the color red;

FIG. 15 is a front elevation of an eighth embodiment of the invention, the front flap of the plastic bag being lined for the color brown;

FIG. 16 is a front elevation of a ninth embodiment of the invention, the front flap of the plastic bag being lined for the color black; and,

FIG. 17 is a front elevation of a tenth embodiment of the invention, the front flap of the plastic bag being lined for the color gray.

Another embodiment is the same as in FIG. 9 except that in this embodiment the front flap of the plastic bag is lined for the color purple;

Another embodiment is the same as in FIG. 12 except that in this embodiment the front flap of the plastic bag is lined for the color gold;

Another embodiment is the same as in FIG. 14 except that in this embodiment the front flap of the plastic bag is lined for the color pink; and

Another embodiment is the same as in FIG. 17 except that in this embodiment the front flap of the plastic bag is lined for the color silver.

The shading in FIGS. 1-8 depicts a color contrast consonant with the visual appearance shown in these drawings. In FIG. 1, a front panel and a rear panel of the plastic bag are transparent, and a front flap of the plastic bag has stippling to show that it has color, and therefore a color contrast is depicted between the colored front flap and the transparent front and rear panels.

The top, bottom, left, and right views of the alternative embodiments in FIGS. 9-16 are as shown in FIGS. 4-8, except that the front flap has the specific color shown in the embodiments of FIGS. 9-16, respectively.
